Term of patent 7 years

To all whom it may concern:

Be it known that I, Viola T. Howard, a citizen of the United States, residing at Saylesville, in the county of Providence and State of Rhode Island, have invented a new, original, and ornamental Design for a Framed Emblem or Similar Article, of which the following is a specification, reference being had to the accompanying drawing, forming a part thereof.

Fig. 1 is a perspective view;

Fig. 2 is a section on line 2—2 of Fig. 1;

Fig. 3 is a face view of one of the parts;

Fig. 4 is a side elevation of the part shown in Fig. 3; and

Fig. 5 is a front view of the framed emblem or

similar article showing my new design, the particular characters being merely illustrative.

The back of the frame and letter are plain to the extent of being devoid of ornamental characteristics.

The dominant feature of the invention is the curve of the face of the frame and cooperating curve of the face of the characters inserted therein.

I claim:

The ornamental design for a framed emblem or similar article, substantially as shown and described.

VIOLA T. HOWARD.
